UNITED STATES PATENT OFFICE.

**HENRY RAMPFEL, OF WEST HOBOKEN, NEW JERSEY, ASSIGNOR TO L. STRAUS & SONS,
A COPARTNERSHIP COMPRISING NATHAN STRAUS, LEE KOHNS, JESSE I. STRAUS,
PERCY S. STRAUS, AND HERBERT N. STRAUS, ALL OF NEW YORK, N. Y.**

DESIGN FOR A PLATE OR SIMILAR ARTICLE.

45,310.

Specification for Design.

Patented Feb. 24, 1914.

Application filed July 23, 1913. Serial No. 780,794. Term of patent 14 years.

To all whom it may concern:

Be it known that I, HENRY RAMPFEL, a citizen of Austria, and a subject of the Emperor of Austria-Hungary, residing at West Hoboken, in the county of Hudson and State of New Jersey, have invented a new, original, and ornamental Design for Plates or Similar Articles, of which the following is a specification, reference being had to the accompanying drawing, forming part hereof.

The figure is a plan view of a plate in which my new design is incorporated.

I claim:—

The ornamental design for a plate or similar article, as shown.

In testimony whereof I affix my signature in the presence of two witnesses.

HENRY RAMPFEL.

Witnesses:

F. HOWARD HUDSON,
B. H. RINEGER.
